UNITED STATES PATENT OFFICE.

WALDEMAR SCHEEL, OF SCHLEUSENDORF, GERMANY.

CAR-COUPING.

SPECIFICATION forming part of Letters Patent No. 596,128, dated December 28, 1897.

Application filed May 18, 1897. Serial No. 637,119. (No model.)

To all whom it may concern:

Be it known that I, WALDEMAR SCHEEL, manufacturer, a subject of the Emperor of Germany, residing at Schleusendorf, near 5 Bromberg, Germany, have invented certain new and useful Improvements in Car-Couplings, of which the following is a specification.

The present invention has reference to an automatic car-coupling which can be uncoupled from either side of the cars, thus doing away with the danger of the man getting caught between the cars while performing the uncoupling.

Figure 1 of the accompanying drawings 15 shows a longitudinal section of the bottom of a car, with a view of the coupling parts A and B in place. Fig. 2 shows a top view of the coupling as arranged on either end of the car. Fig. 3 is a longitudinal section of the coupling 20 parts A and B. Fig. 4 shows the threaded tenon q, the nut r, the worm z, the tenon s, the groove b', and hole b². Fig. 5 shows a section through the tenon q and the pins b³. Fig. 6 shows part of the receptacle d² and the draw- 25 spring k. Fig. 7 is a vertical section through the cylinder l, with the channels a' and a². Fig. 8 shows a longitudinal section of the tenon q, with the groove b' and the hole b². Fig. 9 is a view of the drum u with its axle t in section.

30 The car-coupling is made up of two parts A and B, being arranged alongside of each other on either end of the car. The coupling-hooks b of the part A are pivotally fastened at c to the tenon d and are constantly pressed out- 35 wardly by the flat springs a. The noses f, coming in contact with the stops d', prevent the hooks b from opening too far. The cylindrical part g of the tenon d rests in the receptacle d² and has a groove i provided around 40 its circumference. A draw-spring k, fastened with one end to the receptacle d², with the other end to the tenon d and lying within the said groove i, tends to always keep the coupling-hooks b in the position shown in Fig. 3.

45 The part B consists of a hollow cylinder l, having two conical rings m n and two slots o o, these latter being arranged opposite each other and reaching to the foot of the conical ring n. The parts A and B are connected by 50 the cross-piece p, from which branches off the threaded tenon q. The nut r, serving as a worm - wheel, is screwed partly upon this

tenon q, partly fits loosely over the tenon s, the latter being fastened to the bottom of the car. The nut r engages with the worm z, having the axlet. This axlet also carries the drum u, upon which the chain w, kept under tension by the spring v, is wound when the axle t is rotated by the handle x. When two cars are being pushed together, the coupling-hooks 60 b slide into the cylinder l and catch in the slots o o, thereby coupling the cars. One coupling part A and one coupling part B being provided on either end of the car a safe and secure coupling is assured.

In case the cars are to be uncoupled the nut r, by means of the handle x and worm z, is rotated, with the effect of pushing part B farther into part A. The coupling-hooks b, pressed together by the conical ring n, glide into the 70 channel or groove a', Fig. 3, which latter follows the inner wall of the cylinder l slantingly for a quarter of a circle. The hooks b finally reach the bottom of this channel a', and by rotating the handle x back into its original 75 position, thereby withdrawing part A from within part B, are removed from the channels or grooves a². The draw-spring k draws the hooks b back again in the position shown in Fig. 3. In the tenon q, branching off from 80 the cross-piece p, two grooves b' are provided, being arranged opposite each other and ending in the holes b², Figs. 4 and 8. In either one of these holes b² a pin b³, Fig. 5, is inserted, which pins reach almost to the lateral edge of the car-bottom. If the cars are 85 to be uncoupled, these pins b³ are lifted out of the holes b² and the threaded tenon q, and thereby the coupling parts A and B are free to be worked.

Having now particularly described and ascertained the nature of my invention and in what manner the same is to be performed, I declare that what I claim is—

1. In a car - coupler the combination in a 95 coupling part A of the coupling - hooks b, pressed outwardly by the springs a, the noses f, resting against the stops d', these hooks being pivotally fastened on the tenon d, the cylindrical part g of which, having the groove i, rests in the receptacle d², the spring k, fastened to the cylindrical part g within the groove i and to the receptacle d², said hooks to engage in slots o, o, in the hollow cylinder 100

l of the coupling part B, the slanting groove *a'*, the straight groove *a²* and the two conical rings *m* and *n*, substantially as described.

2. In a car-coupler in combination a coupling part A and a coupling part B, connected by the cross-piece *p*, the threaded tenon *q*, branching off therefrom, the nut *r*, the worm *z*, engaging the worm-wheel formed on the

outer surface of said nut *r*, the axle *t*, the drum *u*, the chain *w* and the spring *v*, the axle *t* to be actuated by the handle *x*, substantially as described.

WALDEMAR SCHEEL.
